UNITED STATES PATENT OFFICE.

MILLER H. McMANNON AND ALEXANDER H. POWERS, OF WATERLOO,
ALABAMA.

DESIGN FOR A HAME-HOOK.

SPECIFICATION forming part of Design No. 29,153, dated August 2, 1898.

Application filed May 17, 1897. Serial No. 636,999. Term of patent 7 years.

To all whom it may concern:

Be it known that we, MILLER H. McMANNON and ALEXANDER H. POWERS, citizens of the United States, residing at Waterloo, in the county of Lauderdale and State of Alabama, have invented and produced a certain new and original Design for Hame-Hooks; and we do declare the following to be a full, clear, and exact description of the invention, such as will enable others skilled in the art to which it appertains to make and use the same.

Our invention relates to a design for a hame-hook, which is fully illustrated in the accompanying drawings, in which—

Figure 1 is a perspective view of our design for a hame-repair hook. Fig. 2 is a transverse longitudinal section of the same.

The leading feature of our design consists of a hame-hook formed with two parallel arms 22 of equal length, having coincident passage-ways 34, and a bulged eye 1, formed midway between said parallel arms.

The design consists of a single piece of metal doubled at the point *a*, so that the bulged eye 1 is centrally alined with the hook. Each parallel end 22 has a vertical passage-way 3 and a crescent-shaped passage-way 4 communicating therewith, the upper wall of each crescent-shaped passage-way being inclined downwardly and provided with an acute angular point *e*.

30

Having thus described our design, what we claim, and desire to secure by Letters Patent, is—

The design for a hame-hook, substantially 35 as herein shown and described.

In testimony whereof we hereunto affix our signatures in presence of two witnesses.

MILLER H. McMANNON.
ALEXANDER H. POWERS.
